WATER JET SURF BOARD

Joseph Robert Burress, 307 Williams Drive,
Brownsburg, Ind.

Filed July 21, 1965, Ser. No. 86,228

Term of patent 14 years

(Cl. D71—1)

Fig. 1.

Fig. 4.

Fig. 2.

Fig. 3.

FIG. 1 is a perspective view of a water jet surf board, showing my new design as it appears when viewed from above and ahead of it.

FIG. 2 is a left side elevational view thereof.

FIG. 3 is a bottom plan view thereof.

FIG. 4 is a rear elevational view thereof.

The appearance of the surf board in the right side elevation is the same as that of the left side elevation.

The dominant features of my design reside in the portions shown in full lines.

I claim:

The ornamental design for a water jet surf board, as shown and described.
